(57) **CLAIM**

The ornamental design for a remote control, as shown and described.

DESCRIPTION

FIG. 1 is a perspective view of a remote control according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a remote control according to a second embodiment of our new design.

FIG. 8 is a front view thereof, the left side, right side, top, and bottom views, respectively, of the second embodiment being identical to the left side, right side, top, and bottom views of the first embodiment.

FIG. 9 is a perspective view of a remote control according to a third embodiment of our new design.

FIG. 10 is a front view thereof, the left side, right side, top, and bottom views, respectively, of the third embodiment being identical to the left side, right side, top, and bottom views of the first embodiment.

FIG. 11 is a perspective view of a remote control according to a fourth embodiment of our new design.

FIG. 12 is a front view thereof, the left side, right side, top, and bottom views, respectively, of the fourth embodiment being identical to the left side, right side, top, and bottom views of the first embodiment.

FIG. 13 is a perspective view of a remote control according to a fifth embodiment of our new design.

FIG. 14 is a front view thereof, the left side, right side, top, and bottom views, respectively, of the fifth embodiment being identical to the left side, right side, top, and bottom views of the first embodiment.

FIG. 15 is a perspective view of a remote control according to a sixth embodiment of our new design.

FIG. 16 is a front view thereof, the left side, right side, top, and bottom views, respectively, of the sixth embodiment being identical to the left side, right side, top, and bottom views of the first embodiment.

FIG. 17 is a perspective view of a remote control according to a seventh embodiment of our new design.

FIG. 18 is a front view thereof, the left side, right side, top, and bottom views, respectively, of the seventh embodiment being identical to the left side, right side, top, and bottom views of the first embodiment.

FIG. 19 is a perspective view of a remote control according to an eighth embodiment of our new design; and,

(Continued)

FIG. 20 is a front view thereof, the left side, right side, top, and bottom views, respectively, of the eighth embodiment being identical to the left side, right side, top, and bottom views of the first embodiment.

The rear views form no part of the design and are omitted. The broken lines showing portions of the remote control are for the purpose of illustrating environmental structure and form no part of the claimed design.
